UNITED STATES PATENT OFFICE.

FRANK A. DOWLER, OF LAWRENCE, KANSAS.

WEB-FEEDING APPARATUS.

1,122,878.

Specification of Letters Patent.

Patented Dec. 29, 1914.

Application filed December 10, 1913. Serial No. 805,739.

To all whom it may concern:

Be it known that I, FRANK A. DOWLER, a citizen of the United States, residing at Lawrence, in the county of Douglas and State of Kansas, have invented certain new and useful Improvements in Web-Feeding Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to web feeding apparatus, and more particularly to an apparatus of that character for use in connection with corrugating machines, printing presses, or the like, wherein a continuous strip of paper is run from one roll through the machine onto another roll, and treated in some manner during its travel; the principal object of the present invention being to provide means for retarding the feeding roll as it diminishes in diameter, in order that the pull or "drag" of the continuous sheet may be substantially constant during the entire feeding period. In accomplishing this object, I provide the improved details of structure hereinafter described and illustrated in the accompanying drawings, wherein:—

Figure I is a perspective view of a web feeding apparatus containing my improvements, and illustrating its combination with a main machine of any suitable type; the roller indicated in the illustration merely indicating a printing, corrugating, or like roller. Fig. II is an end view of the retarder, showing the manifold with its valve. Fig. III is a plan view of the retarder, showing the crank case cylinders and manifold. Fig. IV is a central transverse section of the parts illustrated in Fig. III.

Referring more in detail to the parts:— 1 designates an apparatus, such as a printing or corrugating press, upon which the feeding or retarding parts constituting my invention are mounted, and which comprises a roll 2 of the class used in printing presses, or on corrugating machines, and which is yieldingly pressed against a sheet of paper 3, which is carried through the apparatus between a base plate (not shown), and the roll 2.

The sheet 3 may be of substantial length

and is initially wound on a core 4 and supported by means of the shaft 5, from brackets 6 at one end of the main apparatus, and run from the main roll to a similar core 8, on a shaft 9, journaled in bearings 10 on brackets 11 at the opposite ends of the apparatus, so that the continuous sheet of paper is drawn beneath the printing or corrugating roll and treated during such travel. 65

It is a well known fact that considerable more power must be exerted at the winding end of the sheet when the rewinding is started, in order to overcome the weight and friction of the full initial roll, and it is to 70 overcome variation in the pull or drag of the initial roll as its diameter decreases, and to maintain a constant pull on the winding roll, as the weight and consequent work required at that end of the apparatus increases, that 75 I provide my improvements.

Referring first to the winding end of the apparatus: 13 designates a sprocket wheel on the shaft 9, and 14 a chain belt which operatively connects the sprocket wheel 13 80 with a similar wheel 15, on a shaft member 16, which is journaled in bearings 17 adjacent the end of the main frame and is fixed in a crank case 21, which latter is revolvably mounted on a drive shaft 16'. The drive 85 shaft 16' is provided with a pulley wheel 18, which is driven, through a belt 19, from any source of power (not shown).

The crank case 21, which is revolvably mounted on the drive shaft 16' and fixed to 90 the shaft 16, is provided with a plurality of cylinders 22, each having an automatic air intake valve 23, and exhaust valve 24, the latter having a conduit 25 for establishing communication between its respective cylinder and a manifold 26, and that is carried by the conduits and is common to all of the cylinders. 95

The manifold 26 is provided with a pop valve 27, of any ordinary type, whereby air 100 contained within the manifold and fed thereto through the cylinders is automatically relieved when a determined pressure has been reached in the manifold, in order to maintain the pressure and work of the apparatus within determined limits.

Each of the cylinders 22 contains a piston 29 having a rod 30 mounted on a wrist pin 31, that projects from a crank member 32 on the drive shaft 16', so that when the drive 110 shaft is revolved by the prime mover, the pistons are reciprocated in their cylinders to

draw air in through the intake valves, and force air outwardly through the relief valves into the manifold. With this construction, when the prime mover is first started the pistons are operated to compress air within the manifold, so that when pressure of the air within the manifold is sufficient to overcome the load on the shaft 16, rotation of the drive shaft is transmitted to the crank case and the shaft 16 revolved to drive the belt 14 and thereby wind the continuous sheet of paper on the core 8.

As the speed of the drive shaft is constant and necessarily greater than the driven shaft, even when the web is first commencing to wind on its shaft, each revolution of the driven shaft increases the diameter of the roll, and as travel of the web is retarded to insure constant speed of the web over a given point intermediate the unwinding and winding positions, it is apparent that speed of the driven shaft must decrease relative to the speed of the drive shaft as the diameter of the roll increases. It is also apparent that as the speed of the driven shaft decreases the work required for its rotation increases, owing to the additional weight and leverage on the winding shaft, but that as the driven shaft slows down, the ratio between the revolution of the driven shaft and strokes of the piston increases, thereby increasing the relative displacement of air and consequently the efficiency of the transmission, and thereby tending to maintain constant tension on the web. It is also apparent, that if during this operation the pressure within the manifold should exceed that required for operating the pop valve 27, the latter will open to relieve the manifold, thereby providing against accident to the apparatus or breaking of the sheet of paper should it be held unduly on the initial roll.

I provide a somewhat similar device at the initial end of the printing or corrugating press, except that the crank case and parts operatively connected therewith are fixed against revolution with the roll shaft, and the pistons operated constantly with the latter shaft to generate pressure within the manifold; the detail construction of the device comprising a crank case 34, which is mounted on one of the brackets 6 by metal straps, or the like 35 and has a laterally directed collar 36 through which a crank shaft 37 is projected; the crank shaft 37 having an end socket 38 adapted to fit over the end of the roll shaft 5, and being provided with transverse slots 39 for receiving pins 40 on the roll shaft to key the shafts together.

The crank case 34 is provided with cylinders 22 having intake valves 23, outlet valves 24 and conduits 25 communicating with the manifold 26, and having pistons 29 provided with rods 30 having crank connection with the shaft 37; such parts in the present

device corresponding in construction and arrangement with like parts bearing similar numerals in the device at the winding end of the main apparatus; the only difference in such parts being that the crank case is fixed and free from the roll shaft, instead of being revolvable on the shaft as in the first instance.

The manifold 26 in the device on the unwinding shaft is provided with a pop valve 27 similar to that on the winding case, but is further provided with a non-automatic valve 42, the stem 43 of which is provided with a crank member 44.

The crank member 44 has a link 45 connected with a crank member 46 on a shaft 47 that extends across the main frame 1, and is revolvably mounted in bearings 48 on brackets 49 rising from such frame. Fixed on the shaft 47 is an arm 51 of sufficient weight to lower automatically against the frictional tension in the valve 42 and having a roller 52 adapted for bearing on the roll of paper that is to be unwound from the shaft 5.

With a full roll on the unwinding shaft, pull on the web exerts a leverage on the roll and crank shafts proportional to the diameter of the roll, so that the greatest brake power must be exerted when the diameter is greatest and reduced as the diameter is reduced.

When the roll of paper is first placed in the press, the arm 51 is raised so as to revolve the shaft 47 and restrict the opening of the valve 42 to confine air in the manifold and crank case so that the pistons must work against the pressure held in the manifold and crank case, thereby reducing the speed of the crank shaft as its work is increased. As the press continues to operate and the sheet of paper is drawn from the unwinding roll onto the winding roll, the diameter of the unwinding roll decreases and the arm 51 is lowered; the lowering of the arm gradually opening the valve to allow escape of air from the manifold, and thereby gradually decreasing the work of the pistons as the leverage of the roll is decreased. As the pistons have fixed connection with the roll shaft 5, the shaft 5 is decreasingly retarded as the valve 42 is gradually opened, so that the roll pulls back under the same tension as its diameter decreases, and thereby co-operates with the regulating device on the winding end to maintain a constant pressure on the sheet of paper, and a constant pull on the motor; thereby obviating irregularity of the winding operation and insuring better results from the printing, corrugating, or other apparatus with which the regulators are used.

It is apparent that by providing the unwinding regulator with the pop valve,

pressure in the manifold is automatically relieved at a determined point, in order to obviate locking or excess drag on the roll which might result in breaking or stretching of the continuous sheet that is being unwound.

Having thus described my invention, what I claim as new therein and desire to secure by Letters-Patent, is:-

- 10 1. A web feeding apparatus comprising a shaft adapted for carrying a rolled web, a fluid pressure regulator connected with said shaft and provided with a valve, and a weighted arm adapted for following contact with the rolled web and having crank connection with said valve, whereby the valve is opened to vary the pressure in the regulator proportionately to the variation of the diameter of the roll.
- 15 2. Web feeding apparatus comprising a shaft for carrying a rolled web, an air-pump having a piston operatively connected

with the shaft, a valve for controlling pressure in said pump, and means operatively connected with the valve and adapted for 25 following contact with the web roll for automatically varying the valve opening as the diameter of the roll is altered.

3. Web feeding apparatus comprising a web shaft, a pump having a piston operatively connected with said shaft, a valve for controlling pressure in said pump, a stem projecting from said valve, and a weighted arm adapted for following contact with a roll on said shaft, and having 30 crank connection with said valve stem, whereby the valve is actuated as the diameter of the roll is varied.

In testimony whereof I affix my signature in presence of two witnesses.

FRANK A. DOWLER.
